CLAIM

The ornamental design for an illuminator housing, as shown and described.

DESCRIPTION

FIG. 1 is a perspective view of an illuminator housing showing our new design,

FIG. 2 is a front elevational view thereof,

FIG. 3 is a rear view elevational thereof,

FIG. 4 is a left side elevational view thereof,

FIG. 5 is a right side elevational view thereof;

FIG. 6 is top plan view thereof; and,

FIG. 7 is a bottom plan view thereof.

The broken line showing of various regions of the illuminator housing is for environmental purposes only and forms no part of the claimed design.
